G. L. BAILEY.

Door Spring.

No. 17,070.

Patented April 21, 1857.

UNITED STATES PATENT OFFICE.

GILBERT L. BAILEY, OF PORTLAND, MAINE.

DOOR-SPRING.

Specification of Letters Patent No. 17,070, dated April 21, 1857.

To all whom it may concern:

Be it known that I, GILBERT L. BAILEY, of Portland, in the county of Cumberland, the State of Maine, have invented a new 5 and useful Improvement on Door-Springs for Closing Doors; and I do hereby declare that the following is a full, clear, and exact description of the construction and operation of the same, reference being had to the 10 annexed drawings, and to the letters of reference marked thereon, making a part of this specification, in which—

Figure 1 is a front elevated view of the 15 spring as attached, and Fig. 2, a bird's-eye view of a section showing the position of the lever when the door is partly open.

The nature of my invention consists in 20 providing a volute, coniform spring, which is pressed upon by a lever when the door is opened, and its tendency to resume its original shape, closes the door by forcing the outer end of the lever, which has a roller attached, to the outer end of a guide fastened to the casing, and so formed as to cause the 25 greatest pressure on the door when it is nearly shut.

To enable others skilled in the art to make and use my invention, I will proceed to describe its construction and operation.

30 My spring is made from thick sheet steel or other suitable metal, cut in lengths of about thirteen inches, and tapering in width from one half inch at one end to one quarter inch at the other, or thereabout. The 35 strips are coiled into a volute coniform pile, the apex of the pile being formed of the narrow end of the steel strip. This spring is properly tempered, and placed on a thin plate of cast iron, or other metal, and is 40 movable thereon, and from which projects a post A one and one half inches, with a slot in its outer end. This plate is screwed to the door T, near the top of the same, as shown in the accompanying drawings at o. I do not 45 however, intend to confine myself to the use of the bed-plate o, in connection with the post, as the spring can be placed against the door; but it is preferable to have a hard substance for it to rest upon, consequently 50 I employ the bed-plate; and to prevent the spring from working from under the lever L, I cast slight ledges, or flanges, on each edge of the plate.

In the slot of post A is fixed one end of 55 lever L by a pin on which it plays: at the

other end of the lever, is attached a roller, which being grooved on its face, travels on guide X, which guide is of cast iron, and screwed to the casing of the door, in such a position just above the top of the same, 60 and near the line of the hinge, as to allow the end of lever L to pass over the door when it is opened, and under the guide. The distance from the hinge edge of the door at which post A may be placed, varies 65 according to the length of lever L, which may be from ten to fifteen inches long. The volute spring D, being placed on the plate o near post A, the lever is brought down upon its apex, and the roller at the other end is 70 placed against guide X. When the door is opened the roller H follows guide X and passes in toward the hinge of the door, thereby compressing spring D; and the tendency of said spring to resume its conical form, 75 causes it to press against lever L, forcing roller H back to its original position, at the outer end of guide X, thereby closing the door: guide X is made slightly curving 80 from its base toward the door, and just before reaching the outer end, the curve is made less, which gives an increased pressure on the door just as it is closing.

Some of the advantages of this door spring over most others in use, are, that it 85 gives the greatest pressure on the door when shut, and by the passage of the roller end of the lever in toward the hinge, the pressure is relieved or equalized, when the door is opened wide. It is durable, inasmuch as the spring has but little travel, and consequently is not liable to break readily. There is also a great advantage in applying 90 this peculiar formed spring, which is sufficiently powerful, and occupies but a small 95 space: and finally the whole is manufactured at a far less cost than any other good door spring.

The acting force of the spring D may be increased or diminished, by moving it farther from, or nearer to, the fulcrum of the lever, which is post A: this is an important advantage, and very convenient when applying it to doors of different sizes. I have also thought of various ways in which a rubber spring could be applied, instead of the steel one, using the same lever, roller and guide, and accomplishing the same results.

I do not claim either of the within described parts separately in themselves, as 110

of my invention: neither do I claim in a door spring, making the pressure greatest when the door is closed: but

I do claim as my invention or improvement and desire to secure by Letters Patent—

The use of the volute coniform spring D, in connection with post A, lever L and guide

X; the whole arranged and operating, substantially in the manner and for the purpose 10 set forth.

GILBERT L. BAILEY.
